UNITED STATES PATENT OFFICE.

BENJAMIN A. MOELLER, OF SAN DIEGO, CALIFORNIA.

BEDCOVER-HOLDING DEVICE.

Application filed December 13, 1927. Serial No. 239,731.

My invention relates to bed cover holding devices of the character embodied in my co-pending application, Serial Number 189,977, filed May 9, 1927.

5 It is a purpose of my present invention to reduce the manufacturing costs, to simplify the structure and mode of application of the bed cover holding device, and to make provision for tucking in the covers at the 10 sides of the bed.

I will describe only one form of bed cover holding device embodying my invention and will then point out the novel features in claims.

15 In the accompanying drawings:

Fig. 1 is a view showing in top plan one form of bed cover holding device embodying my invention and in applied position to a bed spring, the latter being shown in dash 20 lines;

Fig. 2 is an enlarged fragmentary vertical sectional view taken on the line 2—2 of Fig. 1 and showing the device in applied position to a mattress and the bed covering therefor;

25 Fig. 3 is an enlarged view showing one of the attaching devices for the bed cover engaging member as applied;

Fig. 4 is a view showing the attaching device in edge elevation and applied;

30 Fig. 5 is an enlarged detail perspective view of one of the clamps embodied in the attaching devices.

In carrying out my invention, I provide a bed cover engaging member designated 35 generally at M and constructed of a single length of rigid material such as steel or the like and which is bent to form an elongated yoke corresponding in length to the width of the bed covering to which it is applied. This 40 member comprises a rail 15 terminating at its ends in U-shaped portions 16 and terminal extensions 17, the portions and extensions being reversely disposed as clearly illustrated in Fig. 1.

45 For securing the member M to a bed spring, and in a manner to securely hold the bed clothing against being pulled loose at the foot of the mattress, I provide a pair of attaching devices A and A', and each of which consists 50 of a clamp 18 shown in detail in Fig. 5 as consisting of a strap of resilient metal bent to provide jaws 18^a and 18^b connected by a curved portion 18^c. Openings 18^d are formed at corresponding points in the jaws 18^a and 55 18^b through which is extended a screw threaded bolt 19 having a squared head 20. In the

applied position of the clamp, as illustrated in Figs. 3 and 4, the curved portion 18^c embraces the upper frame F of the bed spring, and with the bolt 19 extended through the 60 jaws of the clamp and a nut 21 applied to the bolt, it will be clear that the clamp can be brought into secured gripping relation to the spring frame so as to lock the device against movement on the frame. The nut 21 65 constitutes a clamp actuating element for constricting the clamp into gripping engagement with the bed spring frame and in the present instance is in the form of a disk provided adjacent its perimeter with a circular 70 series of perforations 22 designed for the purpose of receiving one of the extensions 17 of the member M and thereby connecting the member M to the attaching devices.

As shown in Fig. 4, the perimeter of each 75 nut is knurled to facilitate manual rotation thereof, and a washer 21^a is interposed between the clamp and the nut to insure ready rotation of the nut on the bolt. By reason of the annular series of perforations at least one 80 opening is exposed above the frame F irrespective of the adjustment of the nut in order to permit insertion of the member extension 17 thereinto. The bolts 19 for the two devices are reversely threaded so that any pulling 85 action exerted on the member M will tend to rotate the nuts upon the bolts in a direction to feed the nuts further onto their respective bolts so as to co-operate with the heads of the latter in constricting the clamps 18 on 90 the bed spring frame.

In Fig. 2 I have shown the member M in applied position to a double length blanket B, the rail 15 being extended through the folded end of the blanket so as to hold such end just beneath the foot end of the mattress. The 95 entire member M is disposed between the mattress and the upper frame F so that the mattress serves to hold the member against upward movement on the nuts 21. With the extensions 17 projected through those openings of the nuts 21 disposed above the frame F, it will be clear that pulling of the blanket upwardly toward the head end of the mattress will be ineffective to disengage it from the member and, consequently, the blanket will 100 be held against pulling loose at the foot of the mattress. Any pulling action exerted on the member M in the direction of the foot of the mattress will tend to rotate the nuts 21 inwardly on the bolts 19 by reason of the reverse 105 threading of the nuts, as described, thereby 110

causing the nuts and heads of the bolts to co-
operate in constricting the clamps on the bed
spring frame and thus cause the clamps to
more firmly grip the frame. It will thus be
5 clear that the greater the tension imposed on
the blanket the more firmly will the clamps
grip the bed spring frame so as to insure that
the clamps will remain secured in fixed posi-
10 tions on the frame. When the blanket B is
superimposed on or used as a closure or en-
velope for the other bed covering, it will be
clear that the blanket will function to prevent
the other covering from pulling loose at the
15 foot of the mattress.

15 By reason of the U-shaped portion 16, no
obstacles are presented at these points in
relation to the mattress to prevent the bed
covering from being tucked in at the sides of
the bed, and, consequently, the covering may
20 be tucked in in the usual manner.

25 Although I have herein shown and de-
scribed only one form of bed cover holding
device embodying my invention, it is to be
understood that various changes and modifi-
25 cations may be made herein without depart-
ing from the spirit of the invention and the
spirit and scope of the appended claims.

I claim:

30 1. A bed cover holding device comprising
a bed cover engaging member, clamps at-
tachable to the sides of a bed spring frame,
and adjustable members mounted on the
clamps for securing the latter to said frame
35 and providing means for securing the ends of
said member to said frame.

40 2. A bed cover holding device comprising
a bed cover engaging member, clamps adapted
to embrace a bed spring frame, bolts for se-
curing the clamps in fixed position on the
frame, and nuts threaded on the bolts and
45 having openings receiving the ends of the
member for securing the latter to the nuts.

45 3. A bed cover holding device comprising
a bed cover engaging member, clamps adapted
to embrace a bed spring frame, bolts extend-
ing through the clamps, disks threaded on
the bolts having knurled perimeters and open-
50 ings receiving the ends of the member for se-
curing the latter to the nuts.

50 4. A bed cover holding device as embodied
in claim 3 wherein said bolts are reversely
threaded for the purpose described.

55 5. A bed cover holding device as embodied
in claim 3 wherein the opening of the disks
are arranged in a circular series in the manner
and for the purpose described.

60 6. A bed cover holding device comprising
a bed cover engaging member adapted to ex-
tend across a bed substantially at one extrem-
ity thereof and means for attaching the mem-
ber to a bed spring frame, said member hav-
ing re-entrant bends at its ends to provide
65 recesses into which the bed covers are adapted
to be tucked at the sides of the bed.

65 7. A bed cover holding device comprising

a bed cover engaging member including a
rail inwardly bent U-shaped portions at the
ends of the rail, inward extensions on the ends
of said portions, a pair of attaching devices
70 each including a clamp adapted to embrace
a bed spring frame, a bolt extending through
the clamp, and a disk-shaped nut on the bolt
having an annular series of openings adjacent
its perimeter, said bolts and their nuts being
75 reversely threaded and said openings receiv-
ing said extensions so that any pull exerted
on said member will tend to tighten the nuts
on the bolts.

80 8. A bed cover holding device comprising
a bed cover engaging member, attaching de-
vices capable of being secured to the sides of
a bed spring frame, means for securing the at-
taching devices in fixed positions on the bed
85 spring frame, and means for so connecting
said member to the last means that any pull
exerted on the member will cause said last
means to operate in more firmly securing the
attaching devices to the bed spring frame.

90 9. A bed cover holding device comprising a
bed cover engaging member, clamps attach-
able to the sides of a bed spring frame, means
for securing the clamps in fixed positions on
the bed spring frame, and means for so con-
necting said member to the last means that
95 any pull exerted on said member will cause
said last means to operate to more firmly
secure the clamps to the bed spring frame.

100 10. A bed cover holding device comprising
a bed cover engaging member, clamps capable
of embracing the sides of a bed spring frame,
threaded members extending through the
clamps, and other members threaded on said
105 members and co-operating with the latter in
securing the clamps in fixed positions on the
frame, and means for so connecting the bed
cover engaging member to said other mem-
bers that any pull exerted on the bed cover
110 engaging member will tend to rotate said
other members on the threaded members so
as to coact with the latter in more firmly
securing the clamps to the frame.

115 11. A bed cover holding device as embodied
in claim 10 wherein said other members are
in the form of substantially disk shaped nuts
having a plurality of circumferentially
spaced openings through any of which a por-
tion of the bed cover engaging member is cap-
able of being extended to connect the latter
to the nuts.

120 12. A bed cover engaging member, clamps
capable of engaging the sides of the bed
spring frame, threaded member carried by
the clamps, and other members threaded on
the last members and having means by which
125 the ends of the bed cover engaging member
are connected to said other members.

13. A bed cover engaging member, clamps
capable of engaging the sides of the bed
spring frame, threaded members carried by
the clamps, and other members threaded on
130

the last members and co-acting with the latter to secure the clamps in fixed positions on the frame, said other members having means by which the bed cover engaging member is connected thereto in such manner that any pull exerted by the bed cover engaging member will tend to more firmly secure the clamps to the frame.

14. A bed cover holding device comprising a bed cover engaging member, clamps adapted to embrace a bed spring frame, bolts for securing the clamps in fixed position on the frame, and nuts threaded on the bolts and having means by which the member is capable of being connected to the nuts. 10

BENJAMIN A. MOELLER.
